UNITED STATES PATENT OFFICE.

CLAYTON STONE HARRIS, OF PHILADELPHIA, PENNSYLVANIA.

DESIGN FOR A MEZZOTINT-PRINT.

SPECIFICATION forming part of Design No. 30,329, dated March 14, 1899.

Application filed December 6, 1898. Serial No. 698,475. Term of patent 7 years.

To all whom it may concern:

Be it known that I, CLAYTON STONE HARRIS, a citizen of the United States, residing at the city of Philadelphia, in the county of Philadelphia and State of Pennsylvania, have invented and produced a new and original Design for a Mezzotint-Print, of which the following is a specification, reference being had to the accompanying illustration, forming part hereof.

The leading feature of my design may be said to be the representation of a field or mat characterized by a fibrous appearance, upon which is displayed, in raised effect, a contrasting background of non-fibrous appearance for the portrait or picture.

In the accompanying illustration, *a* is the field, and its appearance can be best understood by ocular inspection.

b is the background of non-fibrous appearance which contrasts with the field.

c and *d* are respectively light and dark crescents that accentuate the differences in appearance between the field and background.

Having described my invention, what I claim as new, and desire to secure by Letters Patent, is—

The design for a mezzotint-print, substantially as shown and described.

In testimony whereof I have hereunto signed my name.

CLAYTON STONE HARRIS.

In presence of—

ADELE VAN GUNTEK,
SAMUEL J. TAYLOR.
